UNITED STATES PATENT OFFICE

EJALMAR SWANSON, OF CHICAGO, ILLINOIS, ASSIGNOR TO CUMMINS PERFORATOR COMPANY, OF CHICAGO, ILLINOIS, A CORPORATION OF ILLINOIS.

ADJUSTABLE TYPE CARRIER.

Application filed November 8, 1923, Serial No. 673,506. Renewed December 18, 1926.

The invention relates to an adjustable type frame or carrier and among its many useful applications has particular utility in connection with a machine for endorsing or 5 otherwise marking checks or the like.

The invention has for its objects to provide an adjustable type frame or carrier of durable construction which may be easily and conveniently inserted in or removed 10 from the impression roller of a check endorsing or marking machine or the like; to provide an adjustable type carrier composed of few parts so arranged as to render the device readily accessible while in its adjusted position within the impression roller; 15 to provide an adjustable type carrier in which the type bars or slugs may be easily manipulated and readily changed according to the particular purpose for which the machine is to be used; to provide a type carrier of the character described constructed so that the various type bars or slugs are positively maintained in the position to which they have been adjusted; and to provide a type carrier which may be manipulated to change the dates or desired indicia 20 without removing the impression roller from the machine, and which adjustment may be effected during brief stop periods while the machine is in operation.

In addition to the general objects recited above, the invention includes among its objects such other improvements and advantages in construction and operation as are 35 found to obtain in the structures and devices hereinafter described or claimed.

In the accompanying drawings, forming a part of this specification, and showing for purposes of exemplification, a preferred 40 form and manner in which the invention may be embodied and produced, but without limiting the claimed invention specifically to such illustrative instance or instances:

Figure 1 is a vertical longitudinal sectional view through the impression roller of a check endorsing machine and illustrating the preferred embodiment of the present invention attached to said impression roller.

Fig. 2 is a transverse section on line 2—2 of Fig. 1.

Fig. 3 is a similar view showing the method of adjusting the type bars or slugs on the type frame.

Fig. 4 is a plan view on a smaller scale 55 of the structure illustrated in Fig. 1.

Fig. 5 is an enlarged perspective view of one of the removable type bars or slugs.

In the embodiment illustrated in the drawings, the invention is incorporated in a machine that is especially designed for endorsing bank checks. For convenience, the present description will be confined to the illustrated embodiment of the invention as applied to such a check endorsing machine. The various features of the invention are, 60 however, susceptible of use with other machines, and of other valuable applications; hence, the invention is not confined in scope to the specific use and embodiment herein described as an illustrative example. 65

Referring to the drawings, 1 indicates the impression roller of a check endorsing machine removably journaled on trunnions or stub shafts 2 which in turn are suitably supported in uprights or standards 3 of a check endorsing or marking machine. The stub shafts or trunnions 2 may be adjusted longitudinally of the supports with respect to the impression roller 1 by means of suitable set screws 4 carried by the supports 3. The 70 trunnions 2, through the intermediary of the ball bearings 5 of which their ends are fashioned to constitute the cones, support the opposite ends of the printing or type impression roller 1 and provide a substantially frictionless bearing construction for the said type roller. A cam-shaped plate 6 is secured to one end of the impression type roller 1, the purpose of which is to cooperate with other mechanisms in the check 75 endorsing machine to impart the desired intermittent or continuous rotation of the impression roller. This cam plate 6 and the various elements with which it cooperates to produce the desired rotation of the impression roller has been made the subject 80 matter of a separate application Serial No. 596,728, and, forming no part of the present invention, will not be further described. 85

The cylindrical body portion 7 of the impression roller is suitably secured as by screws 7' to the opposite end plates 8 and this body portion is further provided with a type plate 9 on a portion of its outer surface and which carries the fixed type. The type plate 9 is further provided with a central substantially rectangular aperture 10 disposed in alignment with a corresponding aperture 11 on the cover plate 12 of the impression or type roller. The changeable 90

data to be printed on the check or other matter desired to be marked thereon is carried by the adjustable type frame within the impression cylinder and is designed to project through the aligned apertures 10 and 11 when the machine is in operation.

The cover 12 is provided with a pin 13 adapted to be engaged by a hook 14 which is pivoted at 15 to the body of the cylinder, and the cover plate is further provided with a curved spring engaging pin or element 16 which is fastened to the cover at a point substantially opposite the pin 13, the end of the pin or hook 16 being adapted to have a resilient engagement with an aperture 17 in the body of the cylinder. Therefore, it will be apparent that when it is desired to remove the cover plate 12 from the body of the impression roller 1, it is only necessary to swing the hook 14 from engagement with the pin 13 and press the locking pin 16 from its engagement with the aperture 17, and the cover plate carrying the type plate 9 may be bodily removed from the impression cylinder in order to obtain access to the interior thereof.

Formed centrally of the opposing end plates 8 of the impression or type cylinder are a pair of opposed bossed portions 18 carrying a pair of trunnions 19. The trunnions 19 constitute a support for the adjustable type frame adapted to be carried within the impression roller and which type frame is designated as an entirety by 20.

In its preferred embodiment the type frame comprises end members 21 secured to a pair of block members 22, and side plate 21'. Between the blocks 22 are adapted to project the type and resilient carrying frame to be described. The end members 21 are provided with notches or recesses 23 at their lower ends and which are adapted to be engaged and supported by the reduced end portions of the trunnions 19. Locking springs 24 are provided and are secured to the inner faces of the members 21, said springs having apertures 25 adapted to register with the recesses or slots 23 in the side members 21. The locking springs 24 are further provided with depending handle portions 26 by means of which the locking springs and type frame secured thereto may be removably secured upon the opposing ends of the trunnions 19. Access to the handle portions 26 of the locking springs is provided in the nature of suitable holes or apertures 27 formed in the lower part of the cylindrical body of the impression roller.

A type frame supporting spindle or shaft 28 is secured to the horizontal portion 22 of the type frame by means of screws or bolts 29 having a screw threaded engagement with the member 22 and which screws at their lower ends pass through apertures 30 in reduced or flattened portions 30 at each

end of the supporting shaft 28. Coil springs 31 are interposed on the screws 29 and bear against the spindle and horizontal member 22 to insure a resilient and yieldable mounting of the spindle 28 and the parts 70 carried thereby on the type frame.

Mounted upon the spindle 28 is a channel bar or member 32 having depending leg portions 33 provided with apertures for engagement with the shaft 28. The channel bar member further comprises a horizontal channel portion 34 formed by a pair of upstanding channel walls or flanges 35. The several parts described of the channel member 32, including the depending apertured leg members and channel portion, are preferably integrally formed of metal and provide a unitary structure which is mounted upon the supporting shaft 28.

A plurality of tubular separators 36 of any desired number are provided and are rotatably mounted on the stationary shaft 28, the size and number of these rotatable separating elements being governed by the size and number of the type slugs which are intended to be used for a particular operation of the device. A plurality of sheet metal separators or spacing guide plates 37 are provided and loosely mounted upon the shaft 28 between the spacing members 36. The separating plates 37 are cut away at their upper portions to provide recesses 39 adapted to engage and be supported by the upstanding walls of the horizontal channel portion of the channel bar 32.

The desired number and series of type bars or slugs 40 are adjustably carried between the separator plates 37, and each series of slugs is rotatably mounted with respect to the spindle 28 and channel bar 32 by means of endless resilient coil springs 41 passing at their lower portions around the tubular separators or bearing members 36 and, passing at their upper ends over the channel member 32 (Fig. 2). The type slugs 40 are adjustably carried on the springs 41 by means of apertures 42 in the type bars through which the springs are passed. Each type bar is further provided with a second aperture 43 adapted for the reception of an adjusting handle (Fig. 3). The desired indicia to be impressed or stamped upon the check is shown at 44 and, as illustrated in Fig. 5, is in the form of a date. Type bars or slugs, however, may be used having any other form of lettering to be impressed upon the checks should the circumstances so require.

From the foregoing description it will be apparent that when it is desired to change the various type slugs to present a different series of dates or desired indicia in alignment at the upper portion of the type frame carrier, the cover plate 12 is removed from the cylinder and the hook portion 46 of the adjusting tool 45 is inserted in the recesses 130

43 of the type slugs. The resiliency of the endless spring 41 permits any desired type slug to be displaced from its position and inserted in the horizontal channel portion 32 of the type frame (Figs. 3 and 2), at which time when the tool 45 is removed from engagement with the type slug, the spring 41 resumes its normal position and cooperates with the channel member 32 to retain the desired type slug in position to be applied to the check or other paper to be marked when the impression roller is rotated. Each series of type slugs and retaining springs 41 are rotatable on the spindle 28 when the type 10 are being adjusted by the adjusting tool 45, such rotation being permitted by the loose engagement of the tubular separators 36 with the said spindle.

When it is desired to remove the type frame from the impression cylinder it is only necessary to reach the handle portions 24 of the opposed locking springs 23 through the apertures 27 in the impression cylinder and by compressing the handle portions toward 25 one another the apertures 25 are released from engagement with the trunnions 19, thus permitting the type frame to be lifted as an entirety from its normal portion in engagement with the trunnions 19. The type frame 30 and type carried thereby may be removed from the impression cylinder after the cover plate 12 has been removed from the cylinder as heretofore described. It will further be apparent that by the provision of the springs 35 31 a resilient mounting of the channel 32 and type carried thereby is effected with respect to the stationary portion of the type frame and a certain amount of resilience is imparted to the type which projects through the aperture in the impression cylinder, such resilience being desirable when impressing dates or indicia upon the checks.

The invention as hereinabove set forth may be variously embodied within the scope 40 of the claims hereinafter made.

What is claimed is:

1. In an adjustable type frame for check endorsing machines and the like, in combination: a frame adapted to be removably secured within an impression roller, a spindle resiliently supported by said frame, an auxiliary frame mounted on said spindle and having a type-carrying seat, a series of spring members mounted on said frame, a series of type slugs adjustably mounted on each of said series of spring members and adapted to be selectively positioned on said seat, said type slugs being yieldably maintained by said spring members when positioned on said seat, and means carried by each of said type slugs whereby the same are permitted to be selectively positioned on said seat.
2. An adjustable type frame for check endorsing machines, comprising in combination: a frame adapted to be removably secured within an impression roller, a spindle resiliently mounted on said frame, an auxiliary frame mounted on said spindle and having a type-carrying seat, a plurality of endless spring elements carried by said frame and embracing said spindle and said seat, a plurality of type slugs adjustably mounted on said spring elements and adapted to be selectively positioned on said seat, said spring members being adapted to yieldably maintain said type slugs in adjusted position on said seat.
3. An adjustable type frame for check endorsing machines, comprising in combination: a supporting frame adapted to be removably secured within an impression roller, locking means carried by said frame for removably securing the same to said impression roller, a spindle resiliently carried by said frame, an elongated channeled seat mounted on said spindle, a plurality of endless spring members carried by said frame, and a plurality of type slugs carried by said spring members and adapted to be selectively positioned on said channeled seat and yieldably maintained in adjusted position thereon by said spring members.
4. An adjustable type frame for check endorsing machines, comprising in combination: a supporting frame adapted to be removably secured within an impression roller, locking means carried by said frame for removably securing the same to said impression roller, a spindle resiliently supported by said frame, an auxiliary frame carried by said spindle, a channeled seat formed upon said auxiliary frame, a plurality of tubular separators mounted on said spindle, a plurality of spacing guide plates mounted on said spindle between said separators and engaging at their upper ends said channeled seat, a plurality of endless type-carrying spring members arranged between said guide plates and embracing at their upper ends said channeled seat and at their lower ends said tubular separators, and a plurality of type slugs carried by each of said endless spring members and adapted to be selectively positioned on said channeled seat and yieldably maintained thereon in printing position by said spring members, each of said type slugs being provided with means whereby the same are positioned on said channeled seat.
5. A printing mechanism embodying a type seat, a spring member extending transversely of said seat, and a plurality of type slugs carried by said spring element and individually movable with respect thereto, said slugs being adapted to be selectively positioned on said seat and yieldably retained in position thereon by said spring member.
6. A printing mechanism embodying a

4

type seat, a spring member extending across said seat, and a plurality of type slugs slidably mounted on said spring member and adapted to be selectively positioned on said seat and retained in position thereon by said spring member.

7. A printing mechanism embodying a type seat, a spring element, and a plurality of type slugs carried by said spring element and relatively movable with respect thereto for selective mounting on said type seat.

8. An adjustable type frame, comprising in combination: a supporting frame, a spindle carried by said frame, a type-carrying seat mounted on said spindle, and a loop spring on which a plurality of type bars are mounted loosely passing around said spindle and across said seat, whereby said type bars are yieldably maintained on said seat.

9. An adjustable type frame, comprising in combination: a supporting frame, a rod carried by said frame, a type-carrying seat mounted on said rod, an endless flexible loop on which a plurality of type bars are mounted loosely passing around said rod and across said seat, whereby said type bars are yieldably maintained on said seat.

30 10. An adjustable type frame, comprising in combination: a supporting frame, a spindle resiliently carried by said frame, a channeled seat mounted on said spindle and spaced therefrom, said seat being adapted to yieldably maintain a plurality of type slugs thereon, a plurality of endless loop springs loosely passing around said spindle and across said seat, and a series of type slugs mounted on said loop springs, whereby said type bars are yieldably maintained on said seat.

11. An adjustable type frame, comprising

in combination: a supporting frame, a rod carried by said frame, a channeled seat mounted on said rod and spaced therefrom, 45 a plurality of flexible loops loosely passing around said rod and across said seat, and a series of type slugs mounted on said flexible loops, whereby said type slugs are yieldably maintained on said seat.

12. An adjustable type frame, comprising in combination: a supporting frame, a spindle resiliently carried by said frame, a channeled seat mounted on said spindle and spaced therefrom, said seat being adapted 55 to yieldably maintain a plurality of type bars thereon, a plurality of endless loop springs loosely engaging at their lower ends said spindle and at their upper ends said seat, and a series of type bars adjustably 60 mounted on each of said loop springs, whereby said type bars are adapted to be selectively positioned and yieldably maintained by said springs on said seat.

13. An adjustable type frame, comprising 65 in combination: a supporting frame adapted to be removably secured within an impression roller, locking means carried by said frame for removably securing the same to said impression roller, a rod resiliently carried by said frame, a channeled seat mounted on said rod and spaced therefrom, a plurality of endless flexible loops loosely engaging at their lower ends with said rod and at their upper ends said seat, and a 70 series of type bars adjustably mounted on each of said flexible loops, whereby said type bars are adapted to be selectively positioned and yieldably maintained on said seat by said flexible loops.

In testimony whereof I have hereunto set my hand.

HJALMAR SWANSON.
